UNITED STATES PATENT OFFICE.

GILBERT E. NICHOLLS, OF EDGEWOOD, RHODE ISLAND, ASSIGNOR TO THE SWINGRITE CO., INC., OF PROVIDENCE, RHODE ISLAND, A CORPORATION OF RHODE ISLAND.

GOLF-CLUB SHAFT.

Application filed March 11, 1927. Serial No. 174,470.

This invention relates to an improved construction of wooden shaft designed more particularly for use in golf clubs; and the object of this invention is to provide a golf club shaft composed of a plurality of sections of different materials laid side by side, the flexibility of the sections of one material being different from that of the other material, and of a single strip of less flexible material being positioned on the front center line of the shaft to control the flexibility of the shaft in a forward direction.

A further object of the invention is to form the golf club shaft of a plurality of sections of bamboo and a single section of hickory and placing the single section on the front center line of the shaft so as to render more flexible the shaft in a forward direction.

With these and other objects in view, the invention consists of certain novel features of construction, as will be more fully described, and particularly pointed out in the appended claims.

In the accompanying drawings:

Figure 1 is a perspective view of a golf club having a shaft of my improved construction and showing the strip of softer material positioned along the front center line of the shaft.

Figure 2 is a top view looking at the end of the shaft and showing the hickory section as shaded and in line with the central axis through the head.

Figure 3 is a perspective view of a portion of one of the bamboo sections of the shaft.

Figure 4 is a perspective view of a portion of the hickory section of the shaft.

It is found in the building of a sectional golf shaft desirable to provide some means by which its flexibility may be nicely determined and controlled within certain limits so that the desired stiffness of the different shafts may be obtained to suit the requirements of the different players; for instance, different players require what is known as "feel" in the shaft, that is some like the shaft more whippy or flexible than others; and it is found by experts in handling shafts of this character that where a shaft is built up entirely of bamboo strips, it is too stiff for the majority of players and that it requires one or more strips or sections of a softer material to give the required feel to the club

to satisfy the requirements. In some instances, it is found that just the desired amount of flexibility is built into a shaft if all of the sections are made of bamboo with the exception of one single section which may be formed of a more flexible material such as hickory; and the following is a detailed description of one construction of golf club shaft by which just the desired amount of flexibility may be built into the shaft:

With reference to the drawings, 10 designates the shaft of a golf club having a head 11 which may be of wood or metal as is desired, the body of the shaft portion being made up from a plurality of sections 12, each of which is of sector shape to fit closely in contiguous relation throughout their length to form a cylindrical body which may be slightly tapered, end to end as desired, and as illustrated in Figure 1.

The sections 13 are of bamboo which, as is known, is relatively stiff and are formed by splitting a bamboo pole on the desired angle so that the sections are in segmental shape in cross section to properly fit together to form the desired shaft.

It will be noted that the different sections are substantially sector shape and do not come to a sharp edge, but have a slightly curved inner edge 14 due to the natural formation of the stock in some instances. In my improved shaft, one of the sections 15 is preferably of hickory but the shaft may be of any wood having the desired inherent strength and flexibility and which is much more limber or flexible than bamboo.

In order to vary the stiffness of the club, it is found of advantage to place a single strip or section of hickory along the front center line 17 of the shaft, as illustrated, which gives a little more "feel" to the club than as though all the sections were made of bamboo, that is, if all of the sections were made of bamboo the shaft would be too stiff for the majority of players but by inserting a single section of hickory the shaft is rendered a little more flexible or just enough to give the desired whip to the club for most players. If the shaft is too flexible or whippy the head in coming down on a driving stroke springs backward and will give a slice to the ball, while if the shaft is too stiff it lacks driving power and the ball is not driven so far as when the shaft possesses

exactly the proper whip or flexibility. By placing this more flexible section of hickory on the front center line of the club, I obtain the flexibility or whippy effect in that direction leaving the stiffer or less flexible sections on the sides to resist the driving impact of the club with the ball, thus reducing the tortion or twisting effect of the head.

10 From the foregoing it will be seen that I have provided novel means for permitting a certain amount of flexibility or whip in the golf club shaft in the forward direction and at the same time have preserved the necessary stiffness of the shaft in the other direction to assist in resisting the driving impact on the ball.

15 The foregoing description is directed solely towards the construction illustrated, 20 but I desire it to be understood that I reserve the privilege of resorting to all the mechanical changes to which the device is susceptible, the invention being defined and limited only by the terms of the appended 25 claims. In my co-pending patent application Serial No. 174,469 maturing into a patent of even date herewith I have broader and more generic claims to this invention.

I claim:

30 1. A shaft for golf clubs comprising a plurality of sections of bamboo and a single section of wood of a different texture all cemented together, the said single section being positioned on the front center line 35 of the shaft, the sections of said two different woods having adjacent surfaces in planes passing substantially thru the axis of the shaft.

2. A shaft for golf clubs comprising a plurality of sections of bamboo and a single section of hickory all cemented together, the hickory section being positioned to extend along the front center line of the shaft, the sections of said two different woods having adjacent surfaces in planes passing substantially thru the axis of the shaft. 45

3. A shaft for golf clubs comprising a plurality of sections of one kind of wood of a certain flexibility and a single section of another kind of wood having a relatively different inherent flexibility, said two different woods being cemented together, the single section being positioned to extend along the front center line of the shaft to control its flexibility in that direction, the sections of said two different woods having adjacent surfaces in planes passing substantially thru the axis of the shaft. 50

4. A golf club comprising a shaft, a head member on the working end of the shaft, 60 said shaft comprising a plurality of sections of one kind of wood of a predetermined flexibility, and a single section of another kind of wood of a relatively different inherent flexibility, the sections of said two 65 different woods being cemented together, the single section being positioned to extend along the front center line of the shaft and substantially in line with the central axis through the head, the sections of said 70 two different woods having adjacent surfaces in planes passing substantially thru the axis of the shaft.

In testimony whereof I affix my signature.

GILBERT E. NICHOLLS.
